NOVEL METHOD OF PREPARING NUCLEOTIDE IMIDAZOLES

Leon Goldman and Joseph William Marsico, Nanuet, N.Y., and George Washington Anderson, Upper Saddle River, N.J., assignors to American Cyanamid Company, New York, N.Y., a corporation of Maine

No Drawing. Filed Dec. 30, 1959, Ser. No. 862,788

3 Claims. (Cl. 260—211.5)

This invention relates to a novel method of synthesizing nucleotide imidazoles and, more particularly, it relates to the preparation of nucleotide imidazoles by the treatment of a nucleotide with a 1,1'-carbonyldiimidazole.

In order to clarify the exact nature of the chemical compounds of the present invention a few definitions will first be given before proceeding with the description of the invention.

A nucleoside is an N-glycoside of a heterocyclic base, generally a pyrimidine or a purine. Examples of nucleosides are:

(1) Adenosine (or adenine riboside):

(2) Guanosine (or guanine riboside):

(3) Cytidine (or cytosine riboside):

The term "nucleoside" is used herein to include deoxy-nucleosides. Thus, "nucleoside" within the meaning of the present invention includes:

2

(4) Thymidine (or thymine deoxyriboside):

A nucleotide is a phosphate ester of a nucleoside and may be a nucleoside monophosphate or a nucleoside polyphosphate. Examples of nucleoside monophosphates are:

(1) Adenosine-5' phosphate (or muscle adenylic acid or adenosine monophosphate, the latter hereinafter termed AMP):

(2) Guanosine-5' phosphate:

(3) Cytidine-5' phosphate:

(4) Thymidine-5' phosphate:

3

Examples of nucleoside polyphosphates are:

(2) Adenosine-5' triphosphate (hereinafter termed ATP):

A nucleotide coenzyme is a compound including in its structure at least one simple nucleotide moiety. The term "nucleotide coenzyme" is applied to a large and growing group of substances which are vital components of many enzyme systems involved in metabolic processes. Nucleotide coenzymes function in association with specific proteins or apoenzymes, the complete enzyme system being made up of the combination apoenzyme plus coenzyme. Historically, the first nucleotide coenzyme discovered was cozymase, or diphosphopyridine nucleotide, discovered by Harden and Young in 1904. Examples of nucleotide coenzymes are:

(1) Cozymase (or diphosphopyridine nucleotide):

(2) Flavin adenine dinucleotide:

4

(3) Uridine diphosphate glucose:

(4) Coenzyme A:

30 The reaction of adenosine-5' phosphate, dicyclo-hexyl-carbodiimide and imidazole was recently examined by R. W. Chambers and J. G. Moffatt [J. Am. Chem. Soc., 80, 3752 (1958)]. There are obtained 1,3-dicyclohexyl-urea and adenosine-5' phosphoroimidazole as set forth in the following reaction scheme:

The disadvantages of this method of preparing nucleotide imidazoles, heretofore the only method of preparing them, are twofold: (a) the condensation also proceeds in an alternate way, whereby two moles of adenosine-5'

phosphate may condense, giving the undesired symmetrical pyrophosphate;

thus wasting starting material and complicating the isolation procedure; and (b) the incidentally formed dialkyl urea must be removed, an additional isolation requirement.

Our invention is based upon the discovery that nucleotide imidazoles may be prepared in good yield by the treatment of a salt of a nucleotide with a 1,1'-carbonyldiimidazole as set forth in the following reaction scheme:

wherein the Base is either a purine or a pyrimidine moiety, the Sugar is either a pentose or a hexose moiety such as, for example, D-ribose, D-glucose, or 2-deoxy-D-ribose, R is vinylene, substituted-vinylene, o-phenylene, or substituted-o-phenylene, R' is hydrogen or lower alkyl, and B is an organic base such as, for example, imidazole, pyridine, or triethyl amine.

In carrying out the novel method of the present invention for preparing nucleotide imidazoles, the 1,1'-carbonyldiimidazole reagent employed may be, for example, 1,1'-carbonyldiimidazole, 1,1'-carbonyldi(2-methyl)-imidazole, 1,1' - carbonyldi(4 - methyl)imidazole, 1,1' - carbonyldibenzimidazole, 1,1' - carbonyldi(4-nitro)benzimidazole, 1,1' - carbonyldi(6 - nitro)benzimidazole, and the like. The reaction may be carried out in non-aqueous solvents such as, for example, formamide N,N-dimethylformamide, dimethyl sulfoxide, acetonitrile, pyridine, diethyl phosphite, morpholine, dioxane, 1,2-dimethoxyethane, and the like. The reaction is ordinarily carried out at temperatures not substantially exceeding room temperature and over periods of time ranging from less than one minute to an hour or more. Carbon dioxide and an imidazole are the only by-products of the reaction, and it is an advantage of the novel method of the present invention that both by-products are easily separated from the final reaction mixture. The principal advantage of the novel method of the present invention, however, is that it is superior to the previously known method of preparing nucleotide imidazoles insofar as facility of manipulation is concerned.

The reactivity of phosphorylated imidazoles is much greater than that of the ordinary phosphoramidates which also contain a phosphorus-nitrogen linkage. Surprisingly, however, although the phosphorus-nitrogen bond in the nucleotide imidazoles is thus generally activated, it is nevertheless resistant to reaction with water. Hence, it is possible to prepare nucleotide coenzymes and related compounds such as the linear and cyclic oligonucleotides from the nucleotide imidazoles in the presence of water as a solvent without the starting material reacting with that solvent. This circumstance is of critical importance because water is the most convenient solvent for nucleotides.

The following examples illustrate the novel method of preparing nucleotide imidazoles of the present invention.

EXAMPLE 1

Preparation of adenosine-5' phosphoroimidazole

To a solution of 1 mole of adenosine-5' phosphate hydrate and 3 moles of imidazole in anhydrous dimethylformamide at room temperature was added 2 moles of 1,1'-carbonyldiimidazole with stirring. Carbon dioxide was immediately evolved, with the formation of adenosine-5' phosphoroimidazole in solution. This was shown by paper chromatography in isopropyl alcohol-ammonia water (7-1-2) of aliquots taken after 2, 5, and 20 minutes. Ultraviolet absorbing spots were observed corresponding to a major amount of adenosine-5' phosphoroimidazole and a very minor amount of unchanged adenosine-5' phosphate. An additional spot corresponding to adenosine-5' phosphoroamidate was observed, this having been formed by the action of ammonia on adenosine-5' phosphoroimidazole during the chromatographic process. When the chromatogram was sprayed with imidazole detecting reagent, spots appeared corresponding to adenosine-5' phosphoroimidazole and imidazole.

EXAMPLE 2

Preparation of adenosine-5' phosphoroimidazole

To a stirred solution of 1 mole of adenosine-5' phosphate hydrate and 3.14 moles of imidazole in anhydrous dimethylformamide, cooled to 0° C. to -5° C., was added 2 moles of 1,1'-carbonyldiimidazole. After 5 minutes the mixture was cooled to -10° C. to -20° C. and stirred for an additional 10 minutes. Paper chromatography in isopropyl alcohol-1% ammonium sulfate (2-1) showed the reaction mixture to contain mainly adenosine-5' phosphoroimidazole along with a small amount of unreacted adenosine-5' phosphate. Chromatography in isopropyl alcohol-ammonia-water (7-1-2) confirmed the above. An additional spot corresponding to adenosine-5' phosphoroamidate arose from ammonolysis of adenosine-5' phosphoroimidazole during the chromatographic process.

EXAMPLE 3

Preparation of adenosine-5' phosphoroimidazole

To a stirred solution of 1.00 g. of adenosine-5' phosphate hydrate and 0.586 g. of imidazole in 7.5 ml. of anhydrous dimethylformamide at room temperature was added 1.486 g. of 93% 1,1'-carbonyldiimidazole, and after 15 minutes the resulting solution was analyzed by paper chromatography in isopropyl alcohol-ammonia-water (7-1-2), showing complete conversion of adenosine-5' phosphate to adenosine-5' phosphoroimidazole.

We claim:

1. The method of preparing nucleotide imidazoles which comprises treating a salt of a nucleotide and an organic base with a compound of the formula:

wherein R is selected from the group consisting of vinylene, lower alkyl substituted vinylene, o-phenylene and mono-nitro substituted o-phenylene, and R' is selected

from the group consisting of hydrogen and lower alkyl.
2. The method of preparing nucleotide imidazoles which comprises treating a salt of a nucleotide and an organic base with a compound selected from the group consisting of 1,1'-carbonyldiimidazole, 1,1'-carbonyldi(2-methyl)imidazole, 1,1'-carbonyldi(4 - methyl)imidazole, 1,1' - carbonyldibenzimidazole, 1,1' - carbonyldi(4-nitro)

benzimidazole and 1,1'-carbonyldi(6-nitro)benzimidazole.

3. The method of preparing adenosine-5' phosphoroimidazole which comprises treating the salt imidazole adenosine-5' phosphate with 1,1'-carbonyldi-imidazole in an inert solvent at a temperature between -20° C. and +30° C.
